SPEED RECORDING INSTRUMENT

Edward L. Goldsmith, Simsbury, Conn.

Application July 29, 1932, Serial No. 626,137

8 Claims. (Cl. 234—36.5)

My invention relates more particularly to that type of recording instruments which may be employed for recording conditions attending the travel of vehicles along a highway, and an object 5 of my invention, among others, is the provision of an instrument of this type by means of which not only the number of vehicles passing along a certain section of the highway may be determined but the speed of such vehicles will be automatically denoted and each vehicle may also be positively identified.

One form of a recording instrument embodying my invention and in the construction and use of which the objects herein set out, as well 15 as others, may be attained is illustrated in the accompanying drawings, in which—

Figure 1 is a view in longitudinal section through a section of a roadway illustrating in a diagrammatical manner my improved apparatus 20 installed relatively thereto, such apparatus being shown in section.

Figure 2 is a top view of the power unit.

Figure 3 is a view in elevation of the power unit with the motor removed.

Figure 4 is a view in elevation of the power unit looking from the right as shown in Figure 2 with a part of the motor broken off.

Figure 5 is a view in vertical section on a plane passing lengthwise through the axis of the actuating mechanism.

Figure 6 is a view in elevation looking from the left of the device as shown in Figure 3.

Figure 7 is a view in elevation of my improved apparatus embodying a modified construction, 35 the recording frame being shown in vertical section.

Figure 8 is a view in section on a plane denoted by the dotted line 8—8 of Figure 7.

Figure 9 is a top view illustrating another 40 means for recording the conditions relating to travel.

Figure 10 is a view in elevation of the same looking from the right in the illustration in Figure 9.

Figure 11 is a detail view in section on a plane denoted by the dotted line 11—11 of Figure 9.

Figure 12 is a diagrammatic view on reduced scale illustrating the wiring of the device just referred to, parts being broken off for clearness 50 of illustration.

Figure 13 is a diagrammatic view illustrating in simplified form the actual conditions as to a portion of the wiring shown in Figure 12.

Figure 14 is a similar view relating to the wiring shown in Figure 1.

In the accompanying drawings the numeral 10 denotes a roadway having pits 11—12 spaced a certain distance apart and with traps 13—14 covering such pits, said traps being preferably hinged at one edge and with the other edge 5 adapted to be raised as by means of a spring as shown in Figure 1. A starting apparatus is located in the pit 11, as shown at the left in Figure 1, and a stopping or resetting apparatus is located in the other pit 12, or that shown at the right in said Figure 1. A starting switch lever 15 of insulating material is pivotally mounted on a support in the pit 11 and is connected by an actuating rod 16 with the trap 13 on one side of its pivot, its end on the opposite side of said pivot 15 having a contact adapted to slide into engagement with a contact 17 on a movable terminal 18 also of insulating material pivotally mounted on the support hereinbefore mentioned. The terminal 18 is held in contact with the end of the lever 15 as by means of a spring 19 secured at one end to the terminal and at its opposite end to an armature 20 of an electromagnet 21 also mounted on said support. The lever 15 is spring pressed out of engagement with the contact 17. The armature 20 has a notch for engagement with one end of the switch lever 15 to hold the same in engagement with the contact 17 until released therefrom by electrical connections to be herein-after described and operated from the resetting 30 mechanism in the pit 12. This resetting mechanism is similar in construction to the starting apparatus just described and comprises in addition to the trap 14 a resetting switch lever 22 of insulating material having a contact thereon, 35 actuator rod 23, contact 24 on a pivoted terminal 25, and a spring 26, the magnet with its armature being omitted. This resetting apparatus is electrically connected with the starting apparatus and with other parts of the structure in a manner to be hereinafter described.

A power unit is electrically connected with the starting and resetting apparatus hereinbefore mentioned, this unit comprising a controller shaft 27 rotatably mounted in bearings 28 at the 45 upper ends of posts 29 rising from a base plate 30. A tubular support is also mounted in the upper ends of said posts, as in ball bearings located in recesses in said posts, as shown in Figure 5 of the drawings. This support comprises a 50 housing 31 for a sleeve 32 projecting from one end thereof with a plate 33 closing the chamber in the housing and having a hub received in one set of said ball bearings, the outer end of the sleeve 32 also being supported by another set of 55

said ball bearings. A gear 34 is secured to the sleeve 32 and meshes with a pinion 35 secured at the end of a reducing shaft having a driving connection with the main shaft of a motor 36 in 5 a manner that will be readily understood without further and detailed description herein, but as shown in Figure 2 of the drawings.

An electromagnet 37 is secured within the housing 31 to rotate therewith and the armature 10 38 of said magnet is rigidly connected with the shaft 27 as by means of a block secured to the shaft and on which said armature is supported, as shown in Figure 5 of the drawings.

An indicator arm or exhibiting member 39 is 15 operatively connected with the shaft 27, said arm being loosely mounted upon a block secured to said shaft and held in frictional driving contact therewith by means of a spring, as shown in Figure 5. The shaft is rotated backwardly as 20 by means of a returning spring 40 having one end rigidly connected with the shaft and the opposite end secured to a bearing 28. A supporting plate 41 is secured to the base plate 30 and conductor rings 42-43 attached to an insulating plate 44 are supported by the plate 41, a brush 45 being pivoted at the end of the arm 39 to move in contact with said rings.

The ring 42 is cut away as at 46, as shown in dotted lines in Figure 4, for a portion of its periphery, and the ring 43 has graduation marks bearing characters to denote speed. The arm 39 has a buffer plate 47 on the opposite side of its axis from the brush 45, said plate bearing a spring buffer 48 adapted to strike a stop 49 projecting from one of the posts 29, and as shown in Figures 3 and 4 of the drawings.

An insulating bushing 50 is mounted on the sleeve 32 said bushing supporting conducting collars 51-52 from which conductors extend to 40 the opposite poles of the electromagnet 37. Brushes 53-54 extend from binding posts 55-56 secured to one of the supporting posts 29, and as shown in Figures 3 and 5 of the drawings, said posts being adapted to receive wires to be hereinafter described.

A brake disk 57 is secured to the shaft 27 to receive pressure of a spring pressed brake lever 58 pivotally mounted on the base 30 and pressed toward the disk as by means of a spring in a box 59. The brake lever is held in releasing position by means of a lug 60 on an armature 61 of a brake operating magnet 62 mounted on the base 30 and as shown in Figure 6 of the drawings. A camera or exhibiting device 63 is conventionally illustrated in Figure 1 of the drawings, it being understood that said camera will be placed in position to receive the image of a vehicle passing along the road 10, said camera being electrically connected for operation in a manner to be hereinafter described.

A battery 64 may be employed for supplying electric current to the several circuits. The starting circuit comprises wires denoted by the letter *a* extending from the positive pole of the battery to the contact 17 and continued therefrom through the contact on the switch lever 15 to the binding post 56 and from thence to the electromagnet 37. The return wire of said circuit *a* is from said electromagnet to the binding post 55 and from said post to the negative pole of the battery.

A resetting circuit comprising wires *c* extends from the battery along the circuit *a* including the terminal 18 and the lever 15 to a point beyond the latter, and from said point by a wire

5 to a contact on the terminal 25, and from said contact to a contact on the lever 22, when the latter is in circuit closing position, and from thence to one pole of the resetting magnet 21, and from said magnet to the negative pole of the battery. A speed indicating circuit *e* employs the circuit *c* from the battery to a junction with the line *c* before its connection with the magnet 21. From this point the circuit *e* leads to a magnet 63' for operating the camera 63 and 10 from said magnet to and through the magnet 62, the conductor ring 42, the brush 45, when connecting the ring 42 with the ring 43, and from said ring 43 to a junction with the circuit *c* and thence to the negative pole of the battery. 15

In the operation of the device thus far described, if a vehicle is traveling at a certain rate, say over thirty miles per hour, when said vehicle depresses the trap 13 the lever 15 will 20 be swung into engagement with the contact 17 thereby closing the circuit *a* and will be held in this position by engagement with the armature 20. The magnet 37 being thereby excited its armature 38 will act as a clutch to connect the rotating housing 31 carrying the magnet 37 with 25 the controller shaft 27 thereby rotating the latter by the driving gear 34, and carrying with it the indicator or exhibiting arm 39 and the brush 45 mounted thereon, it being understood that the magnet is being continuously rotated by the 30 action of the motor 36. With the apparatus arranged as illustrated herein the pits 11-12 are located at such distance apart that if a vehicle be traveling over thirty miles per hour the brush 45 will continue in contact with both of the 35 rings 42-43 thereby keeping the circuit closed at this point until after action of the trap 14.

When the vehicle depresses the trap 14 the resetting circuit *c* being closed by the lever 22 the current passes from the said lever along the return wire *c* to the magnet 21 and from said magnet to the negative pole of the battery. The magnet being energized the armature 20 is drawn from engagement with the lever 15 and the latter assumes its normal condition to break the 45 circuit at this point.

The closing of the circuit by the lever 22 also establishes the circuit *e* through the magnet 63' for the camera 63 effecting its operation to take a picture of the vehicle passing in front of it. 50 This also energizes the magnet 62 attracting its armature 61 and withdrawing the lug 60 from engagement with the brake lever 58 and permitting the latter to act under the influence of the spring in the box 59. Pressure of the lever against the brake disk 57 stops the operation of the indicating apparatus and the location of the brush 45 with respect to the indicating marks on the index will denote the rate of travel of the vehicle. 55

It will be understood that the power unit may be located some distance from the traps 13-14, as alongside the roadway, and the apparatus thus far described being arranged to denote speeds above thirty miles an hour, as soon as a vehicle has passed over the trap 14, an attendant will reset the mechanism as by pulling down a cord 65 thereby releasing the brake lever 58 from the brake disk 57 and permitting the lug 60 to engage the lever and hold it in unbraking position. 65

If a vehicle should stop between the two traps, or if such vehicle should be traveling at a rate less than thirty miles an hour, no indication of speed will be made. The operation of the trap 70 75

13 will start the mechanism as hereinbefore described, but before the vehicle reaches the trap 14, the brush 45 will have reached the cut away portion 46 of the conductor ring 42 so that the 5 electric circuit will be broken at this point. In this event the plate 44 continues its rotation until the arm 39 contacts with a circuit closer 66 thereby completing the resetting circuit comprising the wires c which is broken at the trap 10 14, such completion taking place through wires i constituting a supplemental resetting circuit, one of said wires i leading from the positive side of the circuit c to a terminal 67 and the other wire i leading from a terminal 68 to the opposite side 15 of the circuit c. Said terminals being pressed into contact the circuit is completed through the positive side of the circuit c to the wire i, terminal 67, terminal 68, wire i, to the negative side 20 of the circuit c, thence to the electromagnet 21 and therethrough to the negative pole of the battery. This energizing of the magnet 21 resets the device as hereinbefore described without a record having been made. In this operation it 25 will be noted that the camera 63 and brake operating magnet 62 will not be operated owing to the fact that the circuit is broken at the rings 42 and 43.

It is evident that the cut-away portion 46 of the ring or disk 42 may be reduced or elongated 30 to determine the taking of a picture at different speeds, or the ring or disk 42 may be adjustable on its axis to accomplish the same purpose and as shown by the slot and screw in Fig. 4 of the drawings.

35 The structure shown in Figures 7 and 8 is, so far as the operating mechanism is concerned, the same as hereinabove described. All that is changed is the recording mechanism which is substituted for that hereinbefore described, this 40 recording mechanism being designed to make a record of every vehicle passing along the roadway 10. The braking mechanism is also omitted. A marking finger 69 is substituted for the indicator arm 39 said finger being supplied with a 45 marker 10 which may be in the form of a pencil or other marker. This marker operates in connection with a chart 71 passing as from a supply roll 72 over a feed roll 73 along a vertically disposed table 74 for supporting the chart during 50 recording operations, to a feed roll 15 and on to a receiving roll 76. The rolls 12 and 76 may be removably mounted as in the side parts of a recording frame 77. The chart or strip 71 may be perforated at its opposite edges to receive prongs 55 from the rolls 13—75 to ensure even movement of the chart. For operating the feeding mechanism a motor in the form of a clock located in a case 78 may be employed, such motor not being shown, the feeding mechanism being so timed 60 that the index 79 bearing time characters will denote the time at which each movement of the finger 69 takes place. This arrangement of the clock mechanism or motor will be readily understood as such is old in the art of recording instruments, and a further and detailed description is therefore omitted herein, it being sufficient to state that the shaft of the motor has a sprocket 80 carrying a sprocket chain 81 which passes around sprockets on the shafts of the roll 75 and 70 a feeding roll 82 for driving the roll 76 by frictional contact therewith. A sprocket chain 83 extends from a sprocket on the roll 75 around a sprocket on the roll 73 for the purpose of driving the latter.

75 In place of the brush 45 described in connec-

tion with the device shown in Figures 1 to 6 a brush 84 is attached to the buffer plate 47, being insulated therefrom and this brush connects contacts 85—86 projecting from a block on the base of the recording mechanism. These contacts have the same function as the rings 42—43 in the other structure, said contacts being included in the circuit comprising the wires e, and as illustrated diagrammatically in Figure 8.

In the operation of this form of recording mechanism when the trap 13 is depressed the 10 operation of rotating the shaft 27 is the same as before, the electrical connections being the same. This swings the arm 69 toward the left, as seen in Figure 8, and the chart 71 being moved by the 15 clock mechanism the time of operation of the arm 69 will be denoted. The graduations 87 with the lines extending therefrom will denote the speed of the vehicle, such speed being determined by the ends of the lines 88 made by the marker, the movement of the arm 69 being stopped when the vehicle passes over the trap 14, in the manner hereinbefore described with respect to the device 20 of the other figures.

Should the vehicle be traveling at a rate less than that provided for by the chart 71 so that the finger 69 will reach the left hand edge of the chart before the vehicle passes the trap 14, the 25 base of the marking finger 69 will strike the terminal 67 pressing it into contact with the terminal 68, thereby completing the circuit comprising the wires i hereinbefore described and operating the magnet 21 to release its armature 20 from the lever 15, thereby resetting the mechanism as hereinbefore explained with respect to 30 the other device.

It will be noted that the brake operating mechanism 62 having been dispensed with in this latter mechanism the magnet for the camera 63 is connected directly with the wire e (or c) extending from the lever 22. The mechanism just described will operate to take a picture by use of the camera only in case a vehicle is traveling at a prohibitive rate of speed which will be indicated by a termination of a line 88 before reaching the crosswise center line 89 shown in Figure 8. In case, however, it is desired to take a picture of every vehicle moving along the roadway, as will frequently be the case, the contacts 85—86 will be long enough not to be disengaged from the brush 84 during the complete movements of the marking finger 69. It will be understood that in actual construction the lines included in the index 79 and those included in the index 87 will extend entirely across the sheet, intersecting each 45 other, in a manner common to charts of this class.

In Figures 9 to 12 inclusive I have shown an arrangement of the recording mechanism which I have found to be extremely efficient and which, I might say, is the preferred construction. The general arrangement of the mechanism is the same as hereinbefore described, with the exception that the starting and stopping apparatus is arranged in the case containing the mechanism hereinbefore described and of which the base plate 30 comprises the back or bottom, said starting and stopping apparatus being connected with the traps by wiring to be hereinafter described, 60 said traps actuating push buttons or similar devices located in the pits 11 and 12 to be actuated by said traps. In this form of the mechanism a reciprocating slide is employed in place of the reciprocating indicating arm 39 and marking 65 70 75 75

finger 69 shown in connection with the other devices.

A pivotally mounted starting switch lever 90 is connected as by a link 91 with an armature 92 of a starting magnet 93, which armature is spring pressed away from the magnet, as shown in Figure 11. The magnet is electrically connected in a manner to be hereinafter described, with a push button or similar device 94 in the pit 11, and the 10 armature 92 is arranged to be held and released by the armature 20 of the resetting electromagnet 21, as in the device shown in Figure 1, the lever 90 having one end bearing an insulated contact 95 in sliding contact with the pivoted 15 terminal 18 and the contact 17 thereon, as in said Figure 1. It will be noted that in connection with this device I have applied the same characters used in the device of Figure 1 to designate members operating substantially in the same 20 manner and having substantially the same functions as said members in Figure 1.

In the construction now being described the speed recording apparatus comprises a recording slide 96 reciprocatingly movable on slide rods 97 projecting from an insulated block 98 secured to a U-shaped mount 99 fitting over the top of and supported by a box 100 secured to a frame 101 rising from the base 30 and including a supporting plate 102 and a bracket 103 projecting from the upper end of said plate, and as shown in Figs. 9 and 10. The box 100 contains a motor in the form of a clock mechanism, which is of standard make. The mechanism is operatively connected with the driving shaft 104 of a timing 35 set of rollers supporting a timing and recording sheet 105 preferably having its edges perforated to receive spurs projecting from the driving roll (not shown) secured to the shaft 104. Said rollers and sheet being of well known construction 40 and operation a further and detailed description is omitted herein as their operation will be readily understood by those skilled in the art.

The outer ends of the rods 97 are loosely supported in insulated bushings in fixtures 106 rotatably supported upon a fixed shaft 107 secured in the bracket 103, said shaft acting as a pivotal mount for the rods 97 and parts supported thereon, so that the mount 99, the block 98 and the slide 96 with parts located thereon may be lifted 50 to permit ready change of sheets 105 when required. A post 108 secured to and rising from the slide 96 acts as an anchorage for one end of a flexible actuator 109 secured to the post as by means of a clip and as shown in Figure 10 of the 55 drawings, said actuator passing around a roller 110, rotatably mounted on the shaft 107, and having its opposite end secured to a disk 111 fixed to the shaft 27. Another disk 112 secured to said shaft has another section 113 of said actuator secured thereto, said section passing upwardly and around a roller 114 loosely mounted on the shaft 107. In order to enable the section 113 of the flexible actuator to be given a quarter turn a block 115 is employed to which the adjacent 60 ends of the actuator are secured, and as shown in Figure 9 of the drawings. This enables the actuator to be passed around a roller 116 mounted on a stud shaft rising from the mount 99 and as shown in Figure 10, this end of the actuator 65 113 being secured to a clip fastened to a tubular post 117 rigidly fixed to the slide 96.

The actuator 109 passes on to the disk 111 at one side, as shown in Fig. 10, and the actuator 113 passes on to the disk 112 at the opposite side, 70 the two actuators thus being wrapped in opposite

directions about the disks, so that one actuator is being wound on its disk while the other actuator is being unwound. The disks turning in the direction indicated by the arrow in Fig. 10, the actuator 109 is wound upon the disk, exerting a pull on the slide 96 and at the same time the actuator 113 is unwound, thus yielding to permit movement of said slide toward the right as viewed in Figs. 9 and 10.

A marker in the form of a prick point 118 is 10 mounted for vertical sliding movement in the tubular post 117, said marker being spring pressed upwardly. Its upper end is engaged by an adjustable screw mounted in the armature 119 of a recording magnet 120 secured to the slide 96, 15 said armature being pivotally mounted in the upper end of the post 108, and as shown in Figure 10 of the drawings.

In the operation of the mechanism just described the shaft 27 is rotated in one direction by the operation of the clutch in the housing 31 in the manner described with respect to the apparatus shown in Figs. 1 to 6, said clutch being released under certain conditions and the shaft 27 being returned to its normal position by means of the spring 40. When the clutch is thrown into operation and the shaft 27 is rotated the disk 111 traveling in the direction of the arrow shown in Figure 10 will move the carriage 96 and the parts carried thereby to the right along the rods 97, the disk 112 permitting movement of the section 113 of the actuator in one direction to allow such movement. The slide 96 will move to an extent determined by the speed of the vehicle traveling along the roadway 10, and when the trap 14 is 20 operated the clutch will be released in the manner hereinbefore described and the spring 40 will return the parts to the position shown in Figure 25 10. At the time of operation of the trap 14 the magnet 120 will be energized, in a manner to be 30 described, the armature 119 will be drawn to the magnet and the prick point or marker 118 will punch the sheet 105 at the point 35 reached by said marker at the time the trap 14 is operated. The sheet 105 will be marked with 40 graduations and lines as shown in Figure 8 so that not only the time will be recorded, but the speed of the vehicle will also be recorded. These 45 marks are omitted from Figure 10 of the drawings as they will be sufficiently understood by the 50 showing made in Figure 8.

A register 121 is supported on the base 30, as 55 shown in Figure 10 of the drawings, this register comprising a counter of ordinary form and construction together with electrical means for operating it, said means comprising a core 122 and a coil 123 which operate actuating mechanism 124. This counter with the actuating mechanism including the electrical means is of the 60 ordinary and standard make and may be purchased upon the market, and therefore a further and detailed description is omitted herein, as the construction and operation will be readily 65 understood by those skilled in the art.

The coil 123 for the register and the magnet 120 for actuating the marker 118 are included in the circuit e, as shown in Figures 12 and 13, the camera 63 with its switch comprising the rings 42-43, the register 121, and the marker 118 being in multiple, as shown particularly in Figure 13, except in the arrangement shown in Figure 12 the wire from the camera to the negative pole of the battery is separate from the return wire from the register and marker to the battery. It 70 will be noted that in the arrangement shown in 75

Figure 12 the slide rods 97 constitute a part of the e circuit.

As hereinbefore explained the starting magnet 93 and its armature 92 are substituted for the 5 rod 16 in Figure 1 as a means for actuating the switch lever 90 which is the equivalent of the switch lever 15 shown in Figure 1, all of this mechanism in the device of Figures 9 to 13 being located in the enclosing casing, as hereinbefore 10 mentioned.

In order to initiate the starting operation of this latter form of mechanism I employ an initiating circuit comprising wires n extending from the positive pole of the battery through the push 15 button 94 and to the starting magnet 93, and through said magnet to a junction with the circuit c as shown in Figure 12. This completes the n circuit to the negative pole of the battery.

The motor 36 and the clock mechanism in the 20 box 100 may be connected with a separate circuit 125 extending from any suitable source of power.

When arranged for operation the switches to the motor and the clock mechanism within the box 100 will be closed and said devices will therefore be in operation, thereby rotating the housing 31 with parts therein and also moving the sheet 105. As to the other switches they are all open at the starting of an operation. When the trap 13 is depressed, as by a vehicle passing over it, the switch comprising the push button 94 is closed, thereby energizing the magnet 93 through the circuit n. This operates the armature 92, thereby swinging the switch lever 90 to close the switch comprising the contacts 17 and 95. This 30 puts the circuit a into operation to energize the magnet 37 and operates the clutch comprising the armature 38, as hereinbefore described to rotate the shaft 27 and the disks 111 and 112 secured thereto. The actuators being wound in opposite 40 directions upon said disks this operation effects a pull upon the flexible actuator 109 and slackens the section 113 of said actuator, thereby moving the slide 96 and parts thereon toward the right as viewed in Figure 10 as hereinbefore set out. The 45 starting switch remains closed during this interval. This mechanism is reset by rotation of the shaft 27 to its position of rest by the spring 40, the actuators operating reversely to the manner above explained.

50 When the trap 14 is depressed, as by the weight of a passing vehicle, the switch comprising the push button in the pit 12 will be closed, thereby establishing the c circuit and energizing the magnet 21 to operate the armature 20 and release the switch lever 90, thereby resetting the starting switch mechanism. The e circuit is also established simultaneously with the c circuit, thereby operating the register or counter 121 to register the event of a passing vehicle. This establishment of the e circuit also energizes the magnet 120, causing the marker 118 to operate to perforate the sheet 105 at the point reached by said marker in the movement of the slide 96.

If the vehicle is traveling fast enough the camera will also be operated at this time in the manner hereinbefore described with respect to the mechanism of Figures 1 to 6. If the vehicle be traveling not to exceed a certain speed the switch comprising the rings 42 and 43 will be opened, 65 thereby rendering the camera inoperative, and the switch 66 will be operated in the manner hereinbefore described to reset the mechanism. This resetting operation will also take place in the event that the vehicle does not reach the second 70 trap or otherwise fails to pass over it.

When the resetting magnet is operated as hereinbefore described, the circuit a will be opened, thereby releasing the clutch 38 and the shaft 27 will be returned to its normal position by the spring 40, and this will also effect a return of 5 the slide 96 to its normal position ready for a succeeding operation.

I claim:

1. A recording instrument including a rotatable support, a drive member mounted on said support and rotatable with respect to said support, means for coupling said support to said drive member, an exhibiting member driven by said support, a control member biased to one position and actuatable to a second position, means effective 10 to latch said control member in said second position upon such actuation, means responsive to such actuation for rendering the coupling means effective to couple the drive member to the support, a stop means, and means responsive to operation of the stop means to release said latch means.

2. A recording instrument including a rotatable support, a drive member mounted on said support and rotatable with respect to said support, means for coupling said support to said drive member, an exhibiting member driven by said support, a member biased to one position and actuatable to a second position, means effective 15 to latch said member in said second position upon such actuation, means responsive to such actuation for rendering the coupling means effective to couple the drive member and the support, a stop means, means responsive to operation of said stop means to release said coupling means, and a 20 movably mounted recording sheet supported in cooperative relation with respect to said exhibiting member.

3. A recording instrument including a movable support, a drive member mounted on said support and movable with respect to said support, means for coupling said support to said drive member, a slidably mounted recording member operatively connected with said support, said recording member including a perforating device, an electric circuit including a member for operating said perforating device, means to control continuity of said circuit, a movable starting control member, and means for operatively connecting said starting control member and said coupling means 40 to effect operation of the latter to operatively connect said drive member and movable support.

4. A recording instrument including a movable support, a drive member mounted on said support and movable with respect to said support, means for coupling said support to said drive member, a slidably mounted exhibiting mechanism operatively connected with said support and including a perforating member and electromagnetic means for actuating said perforating member, a plurality of interconnected electric circuits, said magnetic means being connected in one of said circuits for operation by electrical current therein, means to control a break in said circuits, said means including a movable starting control member biased to one position and actuatable to a second position, means effective to latch said control member in said second position upon such actuation, means for releasing said control member, means included in one of said circuits for electrically operatively connecting said control member and said coupling means and responsive to said actuation to couple the drive member to the support, and means for operating said control member.

5. In a recording instrument having a time driven chart and a marker, the combination of a rotatably mounted support carrying the marker, a time driven member rotatably mounted on said support, electromagnetic means operative to connect the support to the member, a circuit for energizing said electromagnetic means, starting means operative to close said circuit, latching means operative to keep said starting means in closed position, stopping means operative to release said latching means and alternative means for unlatching said starting means operative by the stylus support after said support has rotated to a predetermined position.

- 15 6. A recording instrument including a drive member, an exhibiting member, an actuatable start control means, means retaining said start control means in actuated position, means for resetting said start control means to unactuated position, means responsive to actuation of said start control means for coupling the exhibiting member to the drive member, an exhibiting device, electrical operating means for said exhibiting device, a circuit for said operating means, means driven 20 conjointly with the exhibiting member for conditioning the circuit to said operating means during a predetermined portion of the drive of the exhibiting device, stop control means, means responsive to said stop control means for completing the circuit to the said operating means, and further means responsive to the stop control means for operating said reset means.

7. A recording instrument including a start control member, actuatable from a first to a second position, means biasing said control member to said first position, means operable upon actuation of said start control member to latch said start control member in said second position, exhibiting mechanism including a driven electromagnetic clutch and an exhibiting structure drivable by said clutch when said clutch is energized, a circuit for energizing said clutch completed upon actuation of said start control member, a stop control member, means for releasing said latch, and means responsive to actuation of said stop control member for actuating said latch release means.

15

8. A recording instrument as set forth in claim 7, wherein the start control member includes a switch closed in the second position of the start control member and wherein the stop control member includes a switch closed when said stop control member is actuated, a pair of conducting members, one of which is of a predetermined length, bridging means for said conducting members driven by said exhibiting structure, a camera, and camera operating means included in a circuit containing in series one of said conducting members, said bridging member, the other of said conducting members, said start control switch and said stop control switch.
